[57] CLAIM

The ornamental design for a hand-held protective electric prod, as shown.

DESCRIPTION

FIG. 1 is a side elevational view of the hand-held protective electric prod showing my new design;
 FIG. 2 is a top plan view thereof;
 FIG. 3 is a front elevational view thereof;
 FIG. 4 is a bottom plan view thereof;
 FIG. 5 is a rear elevational view thereof; and
 FIG. 6 is a side elevational view showing the side opposite to that shown in FIG. 1.
